UNITED STATES PATENT OFFICE.

EDWARD D. TAYLOR, OF KALAMAZOO, MICHIGAN.

BROODER.

1,239,637.

Specification of Letters Patent. Patented Sept. 11, 1917.

Application filed July 27, 1914. Serial No. 853,325.

To all whom it may concern:

Be it known that I, EDWARD D. TAYLOR, a citizen of the United States, residing at Kalamazoo, Michigan, have invented certain 5 new and useful Improvements in Brooders, of which the following is a specification.

This invention relates to improvements in brooders.

The main objects of this invention are:

10 First, to provide an improved brooder in which rapid and even circulation of air is maintained through the brooding chamber and one in which the incoming air is effectively warmed and distributed within the 15 brooding chamber.

Second, to provide an improved brooder in which the air has a free circulation within the brooding chamber, hovers and other obstructions being eliminated.

20 Third, to provide an improved brooder having a circular brooding chamber in which the heated air is delivered downwardly and centrally within the brooding chamber thereby effectively overcoming the tendency 25 of the chicks to pile up or crowd against a wall.

Fourth, to provide an improved brooder in which an effective circulation of air is maintained through a brooding chamber provided 30 with entrance and exit doors permitting free entrance and exit of the chicks without interfering with the normal circulation of air within the brooding chamber.

Fifth, to provide in a brooder an improved 35 entrance and exit door structure in which the doors automatically close and may be operated by very young chicks.

Sixth, to provide an improved brooder 40 which is comparatively simple and economical in structure and very easy to regulate or control.

Further objects, and objects relating to structural details, will definitely appear from the detailed description to follow.

45 I accomplish the objects of my invention by the devices and means described in the following specification. The invention is clearly defined and pointed out in the claims.

A structure which is a preferred embodiment of my invention is clearly illustrated 50 in the accompanying drawing forming a part of this specification, in which:

Figure I is a plan view of a brooder embodying the features of my invention.

55 Fig. II is a side elevation thereof, the lamp

housing being shown in vertical central section.

Fig. III is a detail vertical section on a line corresponding to the broken line 3—3 of Fig. I, the thermometer, thermostat and lamp being shown in full lines, the lamp housing being omitted.

Fig. IV is a vertical section on a line corresponding to line 4—4 of Fig. I.

Fig. V is a detail vertical section through 65 the exit on a line corresponding to line 5—5 of Fig. IV.

Fig. VI is a horizontal section on a line corresponding to line 6—6 of Fig. IV.

Fig. VII is a detail view partially in vertical section on a line corresponding to line 7—7 of Fig. I, showing the arrangement of the discharge flue of the heating drum.

In the drawing similar reference characters refer to similar parts throughout the 75 several views, and the sectional views are taken looking in the direction of the little arrows at the ends of the section lines.

Referring to the drawing, the structure illustrated consists of an outer cylindrical 80 sheet metal casing 1 comprising side and top walls and an inner cylindrical sheet metal casing 2 also comprising side and top walls. The casings are of such relative size that when the inner casing is arranged within the 85 outer there is a space between the top walls and an annular space between the side walls.

Vertical partition strips 3 are arranged between the side walls to divide the space between the walls into substantially equal 90 spaces providing a pair of opposed air inlet passages 4 and a pair of opposed air discharge passages 5. Partition strips 6 are arranged between the top walls to provide a connecting passage 7 for the discharge 95 passages 5. The top wall of the outer casing is provided with a discharge flue 8 for the discharge passages. The outer casing is provided with a series of air inlet openings 9 near its bottom for each inlet passage, while 100 the inner casing is provided with a series of delivery openings 10 near its upper end through which the air passes from the inlet passages into the inner casing. The inner casing is also provided with a series of inlet 105 openings 11 near its bottom for each of the discharge passages.

An annular heating drum 12 is fitted within the inner casing. This drum is disposed in a spaced relation to the top of the 110

inner casing and below the air delivery openings 11 so that the incoming air passes across the top of the drum and down through the central opening 13 thereof and 5 is delivered centrally into the brooding chamber below the drum.

The lamp housing 14 for the lamp 15 is mounted at one side of the outer casing and is provided with a flue 16 delivering to the 10 drum through the walls of the inner and outer casing and with an escape flue 17. The escape flue is provided with a damper 18 which is controlled by the thermostat 19 connected by a suitable lever mechanism, designated generally by the numeral 20, to the 15 damper. The thermostat is arranged within the brooding chamber, and, as its structural details form no part of my present invention, I do not further describe the same 20 herein.

The heating drum is provided with a discharge flue 21. This flue is arranged adjacent to the lamp flue 16, a partition plate 22 being interposed between the lamp flue 25 and the discharge flue of the drum so that the heated air and gases must circulate around the heating drum.

I preferably provide a thermometer 25 which is suspended centrally within the 30 brooding chamber from the closure 24 provided for a central opening in the top of the inner casing through which the thermometer may be introduced and removed. This closure and the attached thermometer 35 is adapted to be removed through the flue 8.

With the parts thus arranged the air passes through the inlet openings 9 and air 40 passages 4 and is delivered through the openings 10 into the inner casing above the drum across which it passes and is delivered downwardly through the central opening 13 of the drum centrally into the brooding chamber below the drum.

The circulation of air within the brooding 45 chamber is unobstructed, that is, I do not provide any hovers, deflectors, partitions or the like.

The air is drawn out of the brooding chamber through the openings 11 and the 50 discharge passages 5 and 7 and the discharge flue 8.

This arrangement of parts insures a rapid and constant circulation within the brooding chamber and foul air is continually drawn 55 from the brooding chamber and heated air delivered thereto.

By providing the circular brooding chamber and delivering air centrally thereto I find that in use the chicks cluster or group 60 themselves at the center of the brooding chamber in the path of the warm air and that there is no tendency for them to crowd or pile against the walls, which is likely to cause loss by smothering or injury to the 65 chicks.

To provide a means of entrance and exit which does not interfere with the circulation within the brooding chamber and one which even very young chicks soon accustom themselves to using so that they pass freely 70 to and from the brooding chamber I provide an outwardly projecting passage member 25 which is mounted in a suitable opening in the outer casing to project therefrom and which is provided with a vertical longitudinal partition 26 providing an entrance passage 27 and an exit passage 28. Partitions 29 are interposed between the inner and outer casings to close the inner casing 75 from the air inlet passage 4.

Entrance and exit doors 30 and 31 respectively are preferably formed of mica or other light transparent material so that the chicks can see through the same and at the same time the doors can be readily lifted by 80 the chicks.

The doors are provided with jamb frames 32 arranged within the passages. The door pivots 33 are arranged at the top of the passages so that the doors rest against these 90 jamb frames when closed. The entrance door is arranged at the inner end of the entrance passage, while the exit door is arranged at the outer end of the exit passage, the entrance door being inclined outwardly 95 while the exit door is inclined inwardly.

The doors are preferably arranged so that their lower ends overlap the ends of the bottoms of the passages, as shown. This prevents a chick getting a foothold within 100 the passage and standing in front of the door so as to prevent another chick opening the same. The fact that poultry will keep away from an inclined surface is well known by experienced poultry raisers.

It is found in practice that even very young chicks will enter the passages and push the doors open and that they soon become accustomed to the same so that they pass freely to and from the brooding chamber. 110

By this arrangement of doors the passages cannot become blocked by chicks collecting on the side toward which the doors swing so that the doors remain unobstructed. 115 Further, the doors automatically close so that the circulation within the brooding chamber is not interfered with or materially affected by the opening and closing of the doors.

I have illustrated and described my improved brooder in detail in a form in which I have embodied the same and found highly satisfactory in practical use. I have not attempted to illustrate or describe various 125 modifications which I contemplate as possible as I believe the disclosure made will enable those skilled in the art to which my invention relates to embody or adapt the same as conditions may render desirable. I de- 130

sire however, to be understood as claiming my improvements specifically in the form illustrated as well as broadly within the scope of the appended claims.

5 Having thus described my invention, what I claim as new and desire to secure by Letters Patent, is:

1. In a brooder, the combination of an outer sheet metal cylindrical casing comprising top and side walls, an inner sheet metal cylindrical casing disposed within said outer casing and comprising top and side walls spaced from the top and side walls of the outer casing, partition strips disposed vertically to divide the space between the side walls of said casing into substantially equal spaces providing opposed inlet passages and opposed discharge passages, partition strips disposed between the top walls of said casings providing a connecting discharge passage, the top wall of the outer casing being provided with a discharge flue for said discharge passages, the outer casing having a series of inlet openings for each inlet passage near its bottom and the inner casing having a series of delivery openings for each inlet passage near its top and a series of inlet openings for each discharge passage near its bottom, an annular heating drum fitted within said inner casing and disposed in a spaced relation to the top thereof and below the delivery openings of said inlet passages so that the incoming air passes over the top of the drum and downwardly through the central opening thereof into the brooding chamber below the drum and is discharged from the brooding chamber through the discharge inlets at the sides thereof, the circulation of the air within the brooding chamber being unobstructed, and means for heating said drum.
2. In a brooder, the combination of an outer casing comprising top and side walls, an inner casing disposed within said outer casing and comprising top and side walls spaced from the top and side walls of the outer casing, the space between the walls of said casings being divided into substantially equal spaces providing opposed inlet passages and opposed discharge passages, the outer casing being provided with a discharge for said discharge passages, the upper ends of the inlet passages being cut off from said discharge passages, the outer casing having a series of inlet openings for each inlet passage near its bottom and the inner casing having a series of delivery openings for each inlet passage near its top and a series of inlet openings for each discharge passage near its bottom, an annular heating drum fitted within said inner casing and disposed in a spaced relation to the top thereof and below the delivery openings of said inlet passages so that the incoming air passes over the top of the drum and down-

wardly through the central opening thereof into the brooding chamber below the drum and is discharged from the brooding chamber through the discharge inlets at the sides thereof, and means for heating said drum. 70

3. In a brooder, the combination of an outer casing comprising top and side walls, an inner casing disposed within said outer casing and comprising top and side walls spaced from the top and side walls of the outer casing, the space between the walls of said casings being divided into substantially equal spaces providing opposed inlet passages and opposed discharge passages, the top wall of the outer casing being provided with a discharge flue for said discharge passages, the upper ends of the inlet passages being cut off from said discharge passages, the outer casing having an inlet opening for each inlet passage near its bottom and the inner casing having a delivery opening for each inlet passage near its top and an inlet opening for each discharge passage near its bottom, a heating drum having a central opening therethrough disposed within said inner casing below the delivery openings of said inlet passages so that the incoming air passes over the top of the drum and downwardly through the central opening thereof into the brooding chamber below the drum and is discharged from the brooding chamber through the discharge inlets at the sides thereof, the circulation of the air within the brooding chamber being unobstructed, and means for heating said drum, said inner casing being provided with a central opening through which a thermometer may be introduced and with a removable closure having a thermometer depending therefrom into the brooding chamber, said closure and the thermometer being removable through said discharge flue. 95

4. In a brooder, the combination of an outer casing comprising top and side walls, an inner casing disposed within said outer casing and comprising top and side walls spaced from the top and side walls of the outer casing, the space between the walls of said casings being divided into substantially equal spaces providing opposed inlet passages and opposed discharge passages, the top wall of the outer casing being provided with a discharge for said discharge passages, the upper ends of the inlet passages being cut off from said discharge passages, the outer casing having an inlet opening for each inlet passage near its bottom and the inner casing having a delivery opening for each inlet passage near its top and an inlet opening for each discharge passage near its bottom, a heating drum having a central opening therethrough disposed within said inner casing below the delivery openings of said inlet passages so that the incoming air passes over the top of the drum and down-

air passes over the top of the drum and downwardly through the central opening thereof into the brooding chamber below the drum and is discharged from the brooding chamber through the discharge inlets at the sides thereof, and means for heating said drum.

5. In a brooder, the combination of an outer casing, an inner casing disposed within 10 said outer casing with its walls in a spaced relation to the walls of the outer casing, there being partitions between the casings providing opposed inlet passages and opposed discharge passages, the outer casing 15 being provided with a discharge for said discharge passages, the outer casing having an inlet opening for each inlet passage near its bottom and the inner casing having a delivery opening for each inlet passage near 20 its top and an inlet opening for each discharge passage near its bottom, a heating drum having a central opening therethrough disposed within said inner casing below the delivery opening of said inlet passages so 25 that the incoming air passes over the top of the drum and downwardly through the central opening thereof into the brooding chamber below the drum and is discharged from the brooding chamber through the discharge 30 inlets at the sides thereof, the circulation of the air within the brooding chamber being unobstructed, means for heating said drum, and automatically closing entrance and exit doors for the brooding chamber whereby the 35 circulation of air through the entrance and exit is prevented.

6. In a brooder, the combination of an outer casing, an inner casing disposed within 40 said outer casing with its walls in a spaced relation to the walls of the outer casing, there being partitions between the casings providing opposed inlet passages and opposed discharge passages, the outer casing being provided with a discharge at the top for said 45 discharge passages, the outer casing having an inlet opening for each inlet passage near its bottom and the inner casing having a delivery opening for each inlet passage near its top and an inlet opening for each discharge 50 passage near its bottom, a heating drum having a central opening therethrough disposed within said inner casing below the delivery opening of said inlet passages so that the incoming air passes over the top of the drum 55 and downwardly through the central opening thereof into the brooding chamber below the drum and is discharged from the brooding chamber through the discharge inlets at the sides thereof, and means for heating 60 said drum.

7. A brooder comprising an outer and an inner casing having air inlet and discharge 65 passages between the walls thereof, the outer casing being provided with a discharge at the top for said discharge passage, and with

an inlet opening for the inlet passage near its bottom and the inner casing having a delivery opening for the inlet passage near its top and an inlet opening for the discharge passage near its bottom, a heating 70 drum disposed within said inner casing below the delivery opening of said inlet passage so that the incoming air passes over the top of the drum and downwardly into the brooding chamber below the drum and is 75 discharged from the brooding chamber through the discharge passage, the circulation of the air within the brooding chamber being unobstructed, means for heating said drum, entrance and exit passages for said 80 brooding chamber disposed side by side, doors pivoted at their upper ends within said passages, the entrance passage door being arranged in an outwardly inclined position, the exit passage door being arranged 85 in an inwardly inclined position so that said doors automatically close, said doors when closed being adapted to prevent circulation through said entrance and exit passages.

8. In a brooder, the combination of a cas- 90 ing provided with a brooding chamber, a heating drum disposed in the top of said brooding chamber and having a central opening therethrough, an air inlet passage 95 delivering above said drum so that the incoming air passes over the drum and downwardly through the central opening thereof centrally of the brooding chamber, an air discharge passage opening into said brooding chamber below said drum, a passage 100 member having a longitudinal central partition therein dividing it into entrance and exit passages, and doors pivoted at their upper ends within said passages, the entrance passage door being arranged in an outwardly inclined position at the inner end of the entrance passage to swing inwardly and so that its lower edge laps the edge of the bottom of the entrance passage, the exit door being arranged in an inwardly inclined position at the outer end of the exit passage to swing outwardly and so that its lower end laps the edge of the bottom of the exit passage, said doors being adapted to prevent circulation of air through said 105 passages when closed.

9. In a brooder, the combination of a cas- 110 ing provided with a brooding chamber, a heating drum disposed in the top of said brooding chamber and having a central 115 opening therethrough, an air inlet passage delivering above said drum so that the incoming air passes over the drum and downwardly through the central opening thereof centrally of the brooding chamber, an air 120 discharge passage opening into said brooding chamber below said drum, entrance and exit passages for said brooding chamber, doors pivoted at their upper ends within 125 said passages, the entrance passage door be- 129

ing arranged in an outwardly inclined position to swing inwardly, the exit passage door being arranged in an inwardly inclined position to swing outwardly whereby
5 said doors automatically close, said doors when closed being adapted to prevent circulation of air through said entrance and exit passages.

10. In a structure of the class described, the combination of a casing having a brooding chamber therein, a passage member projecting from said casing and having a longitudinal central partition therein dividing it into entrance and exit passages, and doors
15 pivoted at their upper ends within said passages, the entrance passage door being arranged in an outwardly inclined position at the inner end of the entrance passage to swing inwardly and so that its lower end laps the edge of the bottom of the entrance passage, the exit door being arranged in an inwardly inclined position at the outer end of the exit passage to swing outwardly and so that its lower end laps the edge of the
20 bottom of the exit passage substantially as described and for the purpose specified.

11. In a structure of the class described, the combination of a casing having a brooding chamber therein, a passage member projecting from said casing and having a longitudinal central partition therein dividing it into entrance and exit passages, and doors
25 pivoted at their upper ends within said passages, the entrance passage door being arranged in an outwardly inclined position at the inner end of the entrance passage to swing inwardly, the exit door being arranged in an inwardly inclined position at the outer end of the exit passage to swing outwardly and each door overlapping the
30 end of the bottom of its respective passage.

the outer end of the exit passage to swing outwardly and each door overlapping the 40 end of the bottom of its respective passage, substantially as described and for the purpose specified.

12. In a structure of the class described, the combination of a casing having a brooding chamber therein provided with entrance and exit passages disposed side by side, imperforate doors of transparent material pivoted at their upper ends within said passages, the entrance passage door being arranged in an outwardly inclined position at the inner end of the entrance passage to swing inwardly, the exit door being arranged in an inwardly inclined position at the outer end of the exit passage to swing 55 outwardly.

13. In a structure of the class described, the combination of a casing having a brooding chamber therein provided with entrance and exit passages disposed side by side, 60 doors pivoted at their upper ends within said passages, the entrance passage door being arranged in an outwardly inclined position at the inner end of the entrance passage to swing inwardly, the exit door being arranged in an inwardly inclined position at the outer end of the exit passage to swing 65 outwardly and each door overlapping the end of the bottom of its respective passage.

In witness whereof, I have hereunto set 70 my hand and seal in the presence of two witnesses.
